CLOSURE TOP

Jesse Norden, Kew Gardens, N. Y.

Application April 19, 1950, Serial No. 156,828

2 Claims. (Cl. 229—7)

1
My invention relates to improvements in closures for flat-top containers.

Present day closures are objectionable in that they involve an extra tab for covering the pouring opening; the small lip or apron around the tab does not offer sufficient protection from a sanitary standpoint; and due to projection of the tab, the containers cannot be easily stacked. Furthermore, conventional containers now on the market are weakly constructed. For example, being formed from a single thickness of card board, the closure plug, after being opened only a few times, frequently develops a resiliency which thereafter tends to hold it partially open even when forcibly depressed.

I have overcome these faults in a general sense by the provision of a self-contained, laminated structure in which the lower portion is formed with a pouring opening and an air vent, while the upper portion is a substantial replica of the lower portion with its rear half sealed to the lower portion and its front half hinged to the rear half and carrying a depression which engages the pouring opening, a protective depending flange and a lifting tab. And being laminated and especially designed for use with the type of container covered by my Patent No. 2,572,655, dated October 25, 1951, it is of sturdy construction and resists any tendency of the plug from flopping and staying open.

To the accomplishment of the recited objects and others subordinate thereto, the preferred embodiment of my invention resides in the arrangement and construction of parts shown in the accompanying drawings, described in the following specification, and embraced within the scope of the appended claims.

In said drawings:

Figure 1 is a perspective of a container equipped with my invention.

Fig. 2 is a fragmentary perspective of the upper part of the container showing the cover in open position.

Fig. 3 is a detailed transverse section along lines 3—3 of Fig. 1.

Fig. 4 is a similar view taken along lines 4—4 of Fig. 1, and

Fig. 5 is a top plan of the top illustrating the manner of sealing the laminated sections.

Referring specifically to the drawings, 5—6 50 designate a unit consisting of pairs of superimposed companion sheets of paper or the like. The precise contour of the unit is immaterial, and may be varied in accordance with the particular type 55 of containers for which it is designed.

2
At its forward extremity the lower section 6 is provided with a pouring opening 7 and an air vent 8. The upper section 5 is sealed to the lower section at points 9, 10 and 11 (see Fig. 5), and approximately medially thereof, as at 12, it is scored or weakened to enable the forward portion or flap 13 to be raised or lowered at will. Towards the front of the flap the section is formed with a depression 14 for frictional engagement with opening 7, and slightly in advance of this opening the section is extended to present an operating tab 15 which normally lies relatively flat against the front of the container 16.

The outer edges of both sections 5—6 are 15 fashioned into depending flanges 17—18. The entire flange 18 of the lower section and the rear half of flange 17 of the upper section are permanently clinched against the lip 19 of the container neck 20—thus leaving flange 21 of flap 20 13 free to move when the flap is opened and closed.

In operation, the flap 13 is opened by grasping and lifting tab 15, as illustrated in Fig. 2—the seals 10 and 11 thus being broken. The contents 25 of the container may then be readily poured through opening 7 which I prefer to make relatively small in diameter to insure a free and smooth flow of fluid and the elimination of splashing—the reduced diameter of the opening 30 being made possible by the inclusion of the vent 8.

Closing is effected by forcing the depression 14 into opening 7, which makes for a tight fit—thereby avoiding leakage. This obviously results 35 from the multiple plies of paper employed in the plug 14 and the wall of the opening 7.

Protective flange or apron 21 of the flap reduces to a minimum the possibility of any contamination of the pouring surface before or after use.

40 A container equipped with my flat closure-top is neat and artistic in appearance and gives the impression that it is a one-piece structure. It is completely devoid of projections or other gadgets which clutter it and interfere with proper stacking of the container units.

I claim:

1. The combination with a fibrous container for liquids having a neck provided with a laterally extending peripheral lip, of a closure top comprising two superposed laminated sheets of paper or the like, the bottom sheet fitting upon and being crimped over said lip, and said bottom sheet having a pouring opening therein near a marginal portion thereof, the top sheet structure completely covering the upper face of the

bottom sheet and including a hinge extending medially thereof completely across the same, one half of the top sheet at one side of the hinge being fixedly secured to the bottom sheet to one side of the pouring opening in the latter, said half of the top sheet having its outer peripheral portion extending over and beneath said lip and being clinched against the adjacent marginal portion of the bottom sheet, the other half of the top sheet at the other side of the hinge being free for 10 swinging movement and having an integral depressed portion constituting a plug extending below its lower face to fit into and seal said pouring opening, and said last mentioned movable half of the top sheet when positioned to insert 15 its closure plug into and seal the pouring opening fitting flat against the bottom sheet and extending flush with the other half of the top sheet and presenting therewith a substantially continuous flat outer face, and means sealing the movable half of the top sheet to the bottom sheet.

2. The combination with a fibrous container for liquids having a neck provided with a laterally extending peripheral lip, of a closure top comprising two superposed laminated sheets of paper or the like, the bottom sheet fitting upon and being crimped over said lip, and said bottom sheet having a pouring opening therein near a marginal portion thereof, the top sheet structure completely covering the upper face of the bottom sheet and including a hinge extending medially thereof completely across the same, one half of the top sheet at one side of the hinge being fixedly secured to the bottom sheet to one side of the 30 pouring opening in the latter, said half of the 35

5 top sheet having its outer peripheral portion extending over and beneath said lip and being clinched against the adjacent marginal portion of the bottom sheet, the other half of the top sheet at the other side of the hinge being free for swinging movement and having an integral depressed portion constituting a plug extending below its lower face to fit into and seal said pouring opening, and said last mentioned movable half of the top sheet having an apron portion depending from and extending completely along its outer marginal portion to cover the marginal portion of the bottom sheet forwardly of said pouring opening, said last mentioned movable half of the top sheet when positioned to insert its closure plug into and seal the pouring opening fitting flat against the bottom sheet and extending flush with the other half of the top sheet and presenting therewith a substantially continuous flat outer face.
